TIME RECORDER OR SIMILAR ARTICLE

Dana L. Vickery, Gardner, Mass., assignor to Simplex
Time Recorder Company, Gardner, Mass., a corporation of Massachusetts

Filed Feb. 11, 1966, Ser. No. 1,015

Term of patent 14 years

(Cl. D42—7)

FIG. 1.

FIG. 2.

FIG. 3.

FIG. 4.

FIG. 1 is a perspective view of a time recorder or similar article showing my new design;

FIG. 2 is a side elevational view thereof;

FIG. 3 is a front elevational view thereof; and

FIG. 4 is a rear plan view thereof.

The left-hand side view not shown is a mirror image of FIG. 2; the rear elevation is a flat square surface with no ornamentation.

I claim:

The ornamental design for a time recorder or similar article, as shown.
